UNITED STATES PATENT OFFICE.

EVERETT E. HEAFNER, OF LINCOLNTON, NORTH CAROLINA.

STOP-MOTION FOR TWISTER-FRAMES.

1,375,290.

Specification of Letters Patent. Patented Apr. 19, 1921.

Application filed July 24, 1920. Serial No. 398,608.

To all whom it may concern:

Be it known that I, EVERETT E. HEAFNER, a citizen of the United States, residing at Lincolnton, in the county of Lincoln and State of North Carolina, have invented a certain new and useful Improvement in Stop-Motions for Twister-Frames, of which the following is a full, clear, and exact description.

This invention relates to an improvement in attachments for spinning machinery, especially twisting frames, by which the rotation of the top roll is arrested by means of an arresting device rendered operative upon the breaking of the yarn or thread.

The invention consists of a stop motion for twister frames and the like, comprising, preferably, a substantially U-shaped wire frame adapted to be supported at an upward and forward incline on the twister frame, or some stationary part of the mechanism, and between the upper and lower rolls, and having a swinging or pendent drop wire pivotally supported on the frame and interposed in the path of travel of the thread or yarn and adapted to be so engaged by the thread or yarn as to render the U-frame ineffective to stop the upper roll as long as the thread or yarn is running, and adapted to render said frame effective to stop the upper roll whenever the thread or yarn breaks; a preferred feature of the invention being the provision of a drop wire which will engage the broken end or break a slack thread and prevent it from interfering with the other threads or yarn, as I will proceed now to explain and finally claim.

In the accompanying drawings illustrating the invention, in the several figures of which like parts are similarly designated, Figure 1 is an end elevation showing the stop motion mechanism in position when the thread or yarn is running. Fig. 2 is a similar view with the parts in position when the stop motion has become operative to stop the upper roll. Fig. 3 is a top plan view of the parts shown in the position illustrated in Fig. 1. Fig. 4 is a perspective view of the stop motion detached.

For illustrative purposes, I have shown a portion 1 of a twister frame, having arms or brackets 2 in which is supported a lower roll 3, and arms or brackets 4 in which is supported the upper or feed roll 5, all substantially as usual.

The stop motion comprises a frame 6, sub-

stantially U-shape in plan view, having its corners provided with the friction tongues 7, and its free ends connected by a cross-bar 8 from which last depends the drop-wire 9. This drop-wire has the protruding ends 10 extending above the frame 6, and the connecting cross-bar 11 at its bottom, and opposite said cross-bar are the lateral extensions 12 formed with notches which serve to catch the end of a broken thread or yarn or a slack thread or yarn and hold it from flying out and becoming entangled with other threads or other parts of the machinery. As shown, this drop wire is made in one piece, and the notched portions may be formed by looping the lower ends of the parallel members in line with the cross-bar 11, as shown in Fig. 4. However, the notched extensions may be omitted if desired.

The frame 1 is provided with holes 13 arranged at an incline and slightly below the upper surface of the lower roll 3, to receive the ends 14 of the frame 6 and thereby hold said frame between the upper and lower rolls, at a forward and upward tilt or incline, as clearly shown in Figs. 1 and 2.

The operation would seem to be obvious, but 15 may represent a thread or yarn wrapped once or more around the upper roll 5 and passing thence over the lower roll 3 and to the rear of said roll and engaging the cross bar 11 of the drop wire, as the said thread or wire passes to the receiving member, whatever it may be, below the lower roll. So long as the thread or yarn passing over the cross-bar 11 is intact, the stop motion frame 6 stands out of stopping contact with the roll, because the pull of the thread or yarn on the cross-bar 11 tends to draw the cross-bar 11 toward the lower roll and to cause the ends 10 of the frame 6 to push against the frame 1 and thereby force and hold the frame out of operative contact with the roll. As soon, however, as the thread or yarn breaks, then the draft on the stop motion ceases; the drop wire drops from the forwardly inclined position shown in Fig. 1 to the vertical position shown in Fig. 2 and the stop motion frame is then subject to gravity and the rotation of the rolls, and is drawn in between said rolls until the friction tongues 7 are engaged by the rolls, in which event, the upper roll is lifted out of rolling contact with the lower and its motion arrested and the further feed of the

thread or yarn stopped. Meanwhile, the broken end has been caught in one or the other of the notched extensions 12 of the drop wire, as indicated in Fig. 2, and held 5 from becoming entangled with other threads or parts of the machine and in easy position and reach to be tied by the operative. As soon as the thread or yarn is tied and released, it presses against the cross-bar of 10 the drop wire and acts to restore the stop motion to the position shown in Fig. 1, that is to say, with the friction tongues withdrawn from between the rolls, and the twisting operation thereupon is renewed. Thus 15 the action of the stop motion is automatic, both for stopping the machine and for starting it again, after the accident has been repaired.

Among the advantages incident to this invention, it is noted that the stop motion has 20 only a very slight projection, if any, beyond the front of the rolls, and consequently is out of the way of the operative attending the machine. Practically the whole of the device is at the rear of the rolls. Further, it 25 is to be noted that the operation of the stop motion is practically instantaneous, thereby stopping the thread or yarn from making lap-ups and avoiding waste. The end of a 30 broken thread or yarn will not catch or become entangled with the running end, since the drop wire snatches the thread backward. There is no occasion for the operative to 35 raise the top roll from the bottom roll. The device will not cut the yarn or scratch the rolls and does not need any adjustment after it has been put on the frame. Moreover, the device will stop the top roll when the band or tape that runs the bobbin becomes 40 broken or slack. By the use of my device, an operative may tend several machines. There are no eyes to be threaded and the 45 only attention required by the operative is to see that a broken thread or yarn is tied behind the cross-bar of the drop wire. There is very little if any wear on the rolls, since the tongues only engage the corners of the rolls, while the constant pull of the yarn or thread on the cross-bar lifts the device from 50 the bottom roll sufficiently to afford only very little friction between the two.

Variations in details of construction and arrangement of parts are permissible within the principle of the invention as herein 55 explained and hereinafter claimed.

What I claim is:—

1. A stop motion for spinning machinery, comprising a frame closed at one end and having friction tongues at its closed end and

having its free ends adapted to engage holes 60 in the frame of the spinning machine, said free ends provided with a connecting cross-bar and a drop wire pivotally mounted on said cross-bar and having its free ends projecting above the frame and adapted to engage 65 a fixed portion of the spinning machine.

2. A stop motion for spinning machinery, comprising a frame adapted to be placed between upper and lower rolls about which the 70 thread or yarn is passed, and a drop wire in contact with the thread or yarn to render the frame ineffective to stop the upper roll while the thread or yarn is running and having notches at its lower end to engage 75 the broken end of a thread or yarn and thereupon to release the frame to permit the rolls to draw the frame in between them and thereby raise and stop the upper roll.

3. A stop motion for spinning machinery, comprising a frame adapted to be placed between upper and lower rolls about which the thread or yarn is passed, and a drop wire in contact with the thread or yarn to render the frame ineffective to stop the upper roll 80 while the thread or yarn is running and having a cross-bar at its lower end and extended laterally thereabout and provided with notches to engage the broken end of the thread or yarn or a slack thread or 85 yarn and thereupon to release the frame to permit the rolls to draw the frame in between them and thereby raise and stop the upper roll. 90

4. A stop motion for twister frames and 95 the like, comprising a substantially U-shaped wire frame, provided with means to engage a stationary part of the machine to support said frame at an upward and forward inclination and between the upper and lower 100 rolls, and having a pendent drop wire pivotally supported on the frame and interposed in the path of travel of the thread or yarn and adapted to be engaged by the thread or yarn to render the U-frame ineffective to stop the upper roll while the thread or yarn is running, and when released by the breaking or slackening of the thread or yarn to permit said U-frame to be 105 drawn in between the rolls to raise and stop 110 the upper roll.

In testimony whereof I have hereunto set my hand this 20th day of July A. D. 1920.

EVERETT E. HEAFNER.
